[57] CLAIM

The ornamental design for a combination key holder, pen and flashlight, as shown and described.

DESCRIPTION

FIG. 1 is a top perspective view of a combination key holder, pen and flashlight, showing my new design; FIG. 2 is a side elevation thereof;

FIG. 3 is a top perspective view taken from the opposite side of FIG. 1, with the telescoping head in an extended position; and

FIG. 4 is an elevation as seen from the side opposite FIG. 2.

The broken lines representing the key is shown for illustrative purposes only.
